AUTOMATIC DUMPER FOR CARRIER SYSTEMS

Filed Nov. 2, 1940

UNITED STATES PATENT OFFICE

2,262,727

AUTOMATIC DUMPER FOR CARRIER SYSTEMS

Lester C. Smith, West Hartford, Conn., assignor to The Spencer Turbine Company, West Hartford, Conn., a corporation of Connecticut

Application November 2, 1940, Serial No. 364,074

6 Claims. (Cl. 302—62)

My invention relates to the class of apparatus which are employed in connection with pneumatic conveyers to receive and discharge in a regulated manner material delivered thereto by the conveyor, and an object of my invention, among others, is the production of an apparatus of this kind of simple construction that shall operate in a most efficient manner.

One form of an apparatus embodying my invention and in the construction and use of which the objects herein set out, as well as others, may be attained, is illustrated in the accompanying drawing, in which—

Figure 1 is a view in side elevation of my improved apparatus.

Figure 2 is a similar view on enlarged scale of the lower portion of the apparatus.

Figure 3 is a view in section on a plane denoted by the broken line 3—3 of Figure 2.

Figure 4 is a view in front elevation of that part of the structure shown in Figure 2.

Figure 5 is a view in section on a plane denoted by the broken line 5—5 in Figure 4.

Figure 6 is a detail view illustrating the connection between the cam plate and vacuum equalizing valve.

It is common practice at the present time to remove material from one place and deposit it in another by the use of pneumatic apparatus and my improved structure as illustrated and described herein enables this operation to be performed in an efficient manner by permitting the pneumatic apparatus to freely function to its capacity by causing deposit of the material in a receiver from which it is periodically, automatically discharged in regulated quantities in a manner to keep pace with the flow to the receiver.

In the accompanying drawing the numeral 10 denotes a case or shell constituting a receiver having an inlet 11 to which a conveying tube (not shown) is attached for delivery of material into the shell, said shell also having an outlet 12 connected with any suitable vacuum producing apparatus operated in a well known manner to create a partial vacuum within the shell 10 as will be readily understood. The interior of the shell may be equipped in any suitable manner for separation of the conveyed material from the air, this constituting no part of my present invention and a description and showing thereof being omitted herein. The shell may be supported in any suitable manner, as upon legs 13 and its lower end is preferably tapered to form a hopper 14 into which the material drops from the shell 10.

An interior collector 15 is located at the outlet from the hopper 14 to receive material flowing therefrom, this collector having an inclined bottom 16 and a trap door 17 opening into a chamber in an anterior collector 18 into which the interior collector projects. The edge of the opening from the interior collector 15 is inclined from the vertical, as shown in Figure 2 of the drawing, so that matter accumulated within the 5 chamber in said collector will be freely discharged therefrom into the anterior collector 18 when the door 17 is opened. This door is secured to a shaft 19 mounted in suitably formed bearings in the walls of the anterior collector, said shaft 10 extending through one of said walls and having a clip 20 secured thereto near its outer end with an actuating rod 21 depending therefrom and an actuating roller 22 mounted in the lower end of said rod as shown in Figure 2 of the drawing.

15 The anterior collector 18 has a trap door 23 arranged to close an outlet opening at its front side and the edges of the openings for both of the doors 17 and 23 are suitably packed to prevent entrance of air into the chambers under 20 the influence of vacuum within the collectors. The door 23 is secured to a shaft 24 mounted in bearings suitably formed in the walls of the anterior collector, one end of the shaft extending 25 through and projecting outside of one wall 30 of the collector and having a block 25 secured to said projecting end and having an actuating finger 26 extending therefrom. A cam plate 27 is freely rotatably mounted on the shaft 24 and has a pin 28 projecting laterally from its lower 35 end into position to be moved into contact with the actuating finger 26 when the plate 27 is rotated in a manner to be presently described. A collar 29 is secured to the shaft 24 and a rod 30 supporting a weight 31 is secured to and extends 40 from the collar as shown in Figure 3 of the drawing.

An actuating rod 32 is pivotally attached to the cam plate 27 and extends to an actuating disc 33 secured to the end of a spindle 34' driven 45 by a motor 35 supported on the frame of the apparatus and connected with the vacuum creating power to be driven simultaneously therewith. The disc 33 has a slot 34 extending, in the construction herein shown, not quite half way 50 around the disc somewhat near its edge, but not necessarily concentric therewith, and the rod 32 has a pin 36 riding freely in said slot.

A valve actuating clip 37 is secured on a supporting pin projecting from the side of the cam plate 27 and a valve actuating chain 38 is at-

tached at one end to said clip and at its opposite end to an extension 39 from a valve 40 pivotally mounted on a clamp collar 41 secured to a tube 42 having an opening into the chamber in the anterior collector, the valve normally closing said opening but serving to reduce the vacuum in said chamber when opened in a manner to be hereinafter described.

A vacuum equalizing tube 43 extends from the chamber in the shell 10 into the chamber in the anterior collector 18 thereby keeping said chambers in constant communication and acting to equalize the vacuum in said chambers by extending the vacuum from the shell 10 into the anterior collector.

The operation of the apparatus is as follows: Assuming the parts of the mechanism to be in the positions shown in Figure 1 the trap door 17 is open for the discharge of contents of the interior chamber into the chamber in the anterior collector, the valve 40 being closed and vacuum existing in both the anterior and interior collectors and acting as an aid in keeping the door 23 closed in addition to the weight 31 and while matter is flowing from the interior collector. The actuating disc 33 is continuously rotated in the direction denoted by the arrow in Figure 1. As the disc rotates the parts remain in the position shown while the pin 36 rides along the slot 34 to the end opposite that in which it is shown located in Figure 1. This end of the slot now picks up the pin 36 and draws the actuating rod 32 along, moving the cam plate 21 to the left from the position shown in Figure 1.

The roller 22 resting against the edge of the disc is moved thereby to the left and the rod 21 is similarly moved, thereby closing the trap door 17. When this door closes the vacuum created by the tube 43 acts to maintain a balance of the vacuum in the interior and anterior collectors and as the cam plate continues its movement the roller 22 rides upon the upper edge of the cam plate and acts to temporarily keep the door 17 closed. As the cam plate approaches the end of its path of movement the pin 28 contacts the actuating finger 26, but just before this contact, slack in the chain 38 is taken up, and the chain having been drawn taut by the movement of the cam plate the valve 40 is opened, and the opening in the tube 42 being larger than the opening in the vacuum creating tube 43, the vacuum in the chamber in the anterior collector is destroyed and the pin 28 acting against the finger 26 opens the trap door 23 against the resistance of the weight 31 and the matter in the anterior chamber is permitted to flow therefrom while the interior chamber is receiving material from the hopper 14.

The cam plate 21 having been continuously moving during these operations the slot 34 reaches the position shown in Figure 2 and the end of the slot at the left having reached a point where it no longer exercises force upon the rod 32 the pin 36 is free to move along the slot to the right under the influence of the weight 31, thereby returning the cam plate 21 to the position shown, permitting the door 17 to open under its weight and the door 23 to close under the influence of the weight 31, the parts being in position for repetition of the cycle of movement just explained.

In accordance with the provisions of the patent statutes I have described the principles of operation of my invention, together with the

device which I now consider to represent the best embodiment thereof; but I desire to have it understood that the device shown is only illustrative and that the invention may be carried out by other means and applied to uses other than those above set out.

I claim:

1. An automatic dumper comprising a receptacle having a discharge outlet at its lower end, a receiving chamber into which said outlet opens, said chamber having a discharge opening at its lower end, a trap door hingedly mounted to close said discharge opening, a rotatably mounted cam plate, an operative connection between said trap door and cam plate for operation of said door by said plate, a discharge chamber having a dumping opening at its lower end and positioned to receive the contents of said receiving chamber, a swinging door to close said dumping opening, an operative connection between said swinging door and said cam plate for operation of said door, a valve for opening said discharge chamber to the atmosphere, an operative connection between said cam plate and said valve, a continuously open tubular connection between said receptacle and said discharge chamber, and means operatively connected with said cam plate for the operation thereof.

2. An automatic dumper comprising a receptacle having a discharge outlet at its lower end, a receiving chamber into which said outlet opens and having a discharge opening at its lower end, a swinging trap door to close said discharge opening, a rotatably mounted cam plate, an operative connection between said trap door and cam plate for operation of said door by said plate, a discharge chamber positioned to receive the contents of said receiving chamber and having a dumping opening at its lower end, a swinging door to close said dumping opening, a motor, an actuating disc operatively driven by said motor and having a slot therein, a connecting rod pivotally attached at one end to said cam plate, and a pin at the opposite end of said rod extending into said slot and movable at times therein independently of said disc.

3. An automatic dumper comprising a receptacle having a discharge outlet at its lower end, a receiving chamber into which said outlet opens and having a discharge outlet at its lower end, a swinging door to close said discharge outlet, a rotatably mounted cam plate, an operative connection between said cam plate and trap door for operation of said door by said cam plate, a discharge chamber positioned to receive the contents of said receiving chamber and having a dumping opening at its lower end, a swinging door to close said opening, a rotatably mounted shaft to which said last mentioned swinging door is secured, said cam plate being mounted on said shaft for partial rotation independently thereof, means to rotate said shaft in a direction to close said last mentioned swinging door, a motor, an actuating disc operatively driven by said motor and having a slot therein, a connecting rod pivotally attached at one end to said cam plate, and a pin at the opposite end of said rod extending into said slot and movable at times therein independently of said disc under the force transmitted by said means for rotating said shaft to close said last mentioned swinging door.

4. An automatic dumper comprising a receptacle having a discharge outlet at its lower end, a receiving chamber into which said outlet opens, said chamber having a discharge opening at its

lower end, a trap door hingedly mounted to close said discharge opening, a discharge chamber having a dumping opening at its lower end and positioned to receive the contents of said receiving chamber, a swinging door to close said dumping opening, an operative connection between said swinging door and said trap door for operation of the latter, a continuously open tubular connection between said receptacle and said discharge chamber, and means operatively connected with said swinging door for the operation thereof.

5. An automatic dumper comprising a receptacle having a discharge outlet at its lower end, a receiving chamber into which said outlet opens, said chamber having a discharge opening at its lower end, a trap door hingedly mounted to close said discharge opening, a discharge chamber having a dumping opening at its lower end and positioned to receive the contents of said receiving chamber, a swinging door to close said dumping opening, an operative connection between said swinging door and said trap door for operation of the latter by the former, a valve for opening said discharge chamber to the atmos-

phere, an operative connection between said swinging door and said valve, a continuously open tubular connection between said receptacle and said discharge chamber, and means operatively connected with said swinging door for operation of the latter.

10. An automatic dumper comprising a receptacle having a discharge outlet at its lower end, a receiving chamber into which said outlet opens, said chamber having a discharge opening at its lower end, a swinging trap door to close said discharge opening, a discharge chamber positioned to receive the contents of said receiving chamber and having a dumping opening at its lower end, a swinging door to close said dumping opening, an operative connection between said swinging door and said trap door for operation of the latter by the former, a motor, an actuating disk operatively driven by said motor and having 15 a slot therein, a connecting rod operatively connected at one end with said swinging door for the dumping opening, and a pin at the opposite end of said rod extending into said slot and movable at times therein independently of said disk.

LESTER C. SMITH.
